CLAIM

The ornamental design for a lithium battery pruning shear, as shown and described.

DESCRIPTION

FIG. 1 is a front perspective view of a lithium battery pruning shear embodying my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged detail view of area 9 in FIG. 2.

The broken lines in the drawings illustrate the portions of the lithium battery pruning shear, which form no part of the claimed design.

The dash-dot-dash broken lines in drawings are provided for annotative purposes to graphically indicate the areas of enlargement. The dash-dot-dash broken lines do not represent actual structure and do not form part of the claimed design.
